BARREL-Straightening MECHANISM.

1,323,279.

Specification of Letters Patent.

Patented Dec. 2, 1919.

Application filed October 31, 1917. Serial No. 199,419.

To all whom it may concern:

Be it known that I, FRANK O. HOAGLAND, a citizen of the United States, residing at Hartford, in the county of Hartford and 5 State of Connecticut, have invented certain new and useful Improvements in Barrel-Straightening Mechanism, of which the following is a specification.

This invention relates to a mechanism 10 which is adapted to be used for straightening the bores of gun barrels.

The principal object of the invention is to provide a mechanism which readily enables the operator to take into account and 15 compensate for the character of the curvature which he finds in the gun barrel. The machine is adapted to be readily adjusted to straighten relatively short sharp curvatures or to straighten relatively long gradual 20 curvatures. Other objects of the invention will be apparent from the following specification and claims.

The invention can be embodied in any 25 one of a large number of ways and in the accompanying drawing I have shown a relatively simple embodiment which is entirely suitable for performing accurate work. It will be understood, however, that the drawing is intended to be merely illustrative and 30 is not to be understood as defining or limiting the scope of the invention, the accompanying claims being relied upon for that purpose.

Of the drawings:

35 Figure 1 is a front elevation with certain parts broken away and shown in section.

Fig. 2 is a vertical sectional view taken along the line 2—2 of Fig. 1.

Fig. 3 is a detail view of the adjusting 40 mechanism, this view being taken from the right-hand side of the machine.

Fig. 4 is a detail sectional view taken along the line 4—4 of Fig. 3.

Referring to the drawing, 1 represents 45 the base or pedestal upon which the other parts are supported. Mounted on the base or pedestal is a frame member 2 which is provided at 3 with an anvil having a horizontal top face. The anvil is provided with 50 a longitudinal groove 4 in which are slidably fitted two shoes 5 and 6. These shoes

are adapted to support the gun barrel which is to be straightened.

For applying pressure to the barrel in the proper direction to straighten it when it is 55 resting upon the shoes, I provide a plunger 7 which is preferably secured to or formed integrally with a vertically threaded rod 8. This rod 8 fits a vertical nut 9 which is rotatable in a bearing in the upper part of 60 the frame member 2. For turning the nut 9 there is provided a bevel gear wheel 10 which is preferably formed integrally with the nut, as shown. This bevel gear 10 meshes with a bevel gear 11 on a horizontal 65 shaft 12 which is rotatable in a bearing in the frame member 2. At the outer end of the shaft 12 is a hand wheel 13 by means of which the shaft may be readily turned manually. It will be clear that, by means 70 of the hand wheel, the nut 9 can be turned to raise or lower the plunger 7 by means of the threaded connection between the nut and the rod 8.

Preferably, in order to prevent the rod 75 8 from turning with the nut 9, there is provided a clip 14 which is secured to the frame member 2 and which carries at its inner end a key 15 projecting into a keyway 16 in the rod 8.

In order that the mechanism may be adapted for the straightening of either short sharp bends in a barrel or long gradual bends, the two shoes 5 and 6 are adjustable toward and away from the plunger 7. It is 85 essential that the two shoes be maintained at equal distances from the plunger, or in other words, it is essential that the plunger be at all times midway between the two shoes. I provide an equalizing mechanism 90 whereby I insure the movement of the two shoes to equal extents in opposite directions. As concerns certain phases of the invention, I do not limit myself to any particular form of mechanism for this purpose, but I prefer 95 to provide a shaft 17 which extends parallelly with the groove 4 in the anvil 3. At the center below the plunger 7 the shaft 17 extends through a block 18 which is held against longitudinal movement. At each 100 side of the block the shaft is provided with a collar 19 and these collars engaging the

block hold the shaft against longitudinal movement. The two end parts of the shaft 17 extend respectively through the shoes 5 and 6 and are provided with similar but oppositely inclined threads which are preferably of sharp pitch. Secured to the shoes 5 and 6 and engaging the ends of the shaft 17 are nuts 20 and 21. It will be clear that any rotative movement of the shaft 17 will cause the two shoes to move outward or inward to the same extent, thus maintaining them at equal distances from the plunger. Preferably the pitch of the threads on the shaft 17 is such that either shoe may be moved manually to impart a rotative movement to the shaft and thus move the other shoe in the opposite direction.

Under some circumstances I prefer not to depend solely upon one or the other of the shoes for imparting rotative movement to the shaft 17. It is sometimes desirable to provide a separate mechanism for this purpose and such a mechanism is illustrated. As shown, the anvil 3 carries at its right-hand end a bearing block 22 and the shaft 17 is extended to have a bearing in this block. Secured to the end of the shaft 17 is a pinion 23. A segmental gear 24 meshes with the pinion 23 and is mounted on a pivot pin 25 which has a bearing in the block 22. The segmental gear 24 carries a handle 26 by means of which it may be turned. It will be clear that the operator, by moving the handle 26, can turn the shaft 17 and thus move the shoes 5 and 6 in either direction and to any desired extent, at the same time maintaining them at equal distances from the central plunger 7.

The errors of the barrel to be straightened can be determined in any usual or preferred way. If preferred, a special mechanism may be provided for ascertaining these errors, or they may be noted by sighting through the barrel in the well known manner. The mechanism as illustrated is particularly adapted for use with the sighting method and for the convenience of the operator in sighting I have provided a rest 27 upon which the end of the barrel can be supported. Preferably, as shown, this rest is at an elevation somewhat above that of the shoes so as to support the barrel at an elevation which is convenient for the operator. The operator supports one end of the barrel on the rest 27 and observes the direction of the curvature and also observes whether it is long or short. He adjusts the shoes 5 and 6, preferably by means of the handle 26, in accordance with the length of the curve. Then he places the barrel on the shoes and turns it to the proper position. By turning the hand wheel 13 he moves the plunger downward into engagement with the barrel and applies the required pressure to straighten it. This operation is repeated until all of

the curvatures of the barrel have been removed and it is straight throughout.

It is sometimes desirable to slightly incline the anvil 3 for the convenience of the operator, and, in order that this may be done without disturbing the relationship of the several coöoperating parts, I provide a pivotal connection between the frame member 2 and the pedestal. As illustrated, the pedestal is forked and a depending portion of the frame member is positioned between the two forks. A pivot pin 28 extends through these parts and the frame member with the parts carried thereby may be adjusted on this pivot pin. After adjustment the nut 29 on the pin may be turned to clamp the two forks of the pedestal against the frame member and thus lock the frame member in adjusted position.

What I claim is:

1. In a machine for straightening gun barrels, the combination of a base, a frame carried by the base and having a horizontal recess therein open at one side, two barrel engaging shoes positioned at the bottom of the recess, a plunger projecting into the recess from the top and vertically movable along a line midway between the shoes and intersecting the axis of a barrel on the shoes, a manually operable device at the rear of the frame opposite the open side of the recess for moving the plunger to apply to the barrel any pressure that the operator may deem necessary, and manually operable means for moving the shoes toward or from each other while automatically maintaining them equidistant from the plunger.

2. In a mechanism for straightening gun barrels, the combination of a base, a frame carried by the base and having a horizontal recess therein open at one side, two barrel engaging shoes positioned at the bottom of the recess, a plunger projecting into the recess from the top and vertically movable along a line midway between the shoes and intersecting the axis of a barrel on the shoes, a manually operable device at the rear of the frame opposite the open side of the recess for moving the plunger to apply to the barrel any pressure that the operator may deem necessary, an oppositely threaded longitudinal shaft for moving the shoes toward or from each other while automatically maintaining them equidistant from the plunger, and a handle at one end of the frame adjacent the recess for turning the shaft.

3. In a mechanism for straightening gun barrels, the combination of a base, a frame carried by the base and having a horizontal recess therein open at once side, two barrel engaging shoes positioned at the bottom of the recess, a plunger projecting into the recess from the top and vertically movable along a line midway between the shoes and

intersecting the axis of a barrel on the shoes, a manually operable device at the rear of the frame opposite the open side of the recess for moving the plunger to apply any desired pressure to the barrel that the operator may deem necessary, means for moving the shoes toward or from each other while automatically maintaining them equi-

distant from the plunger, and a barrel rest rigidly secured to the frame adjacent the top 10 of the recess whereby the operator may support the barrel for convenience in sighting.

In testimony whereof, I hereto affix my signature.

FRANK O. HOAGLAND.
